GAEOUS DISCHARGE DEVICES HAVING A FREE AUXILIARY CONTROL ELECTRODE

Alfred H. Faulkner, Chicago, Ill., assignor to Automatic Electric Laboratories, Inc., Chicago, Ill., a corporation of Delaware

Application January 23, 1951, Serial No. 207,308

2 Claims. (Cl. 313—198)

This invention relates to gaseous discharge devices having at least three electrodes.

Gaseous discharge devices of the triode type have the auxiliary control electrode, such as the anode-starter, positioned in the main discharge space, and hence the auxiliary control electrode acquires a potential dependent upon the space charge in the device. As a consequence thereof, the auxiliary control electrode draws current and produces a potential on the circuits connected thereto, and therefore the auxiliary control electrode cannot be treated as a free electrode.

Accordingly, an important object of the present invention is to provide a gaseous discharge device having the auxiliary control electrode free after ionization has transferred to the main gap, and the starting potential has been removed from the auxiliary control electrode.

Another object of the present invention is to provide a cold-cathode type gaseous discharge device having the starter-anode free after ionization has transferred to the main gap, and the starting potential has been removed from the starter-anode.

Other objects will appear upon further perusal of the detailed description taken in conjunction with the accompanying drawing in which:

Fig. 1 is a front elevation view of a gaseous discharge device embodying the present invention.

Fig. 2 is a sectional view taken along the line 2—2 of Fig. 1.

Fig. 3 is a side elevation of a gaseous discharge device embodying the present invention.

As shown in the drawing, a gaseous discharge device 10, such as the cold-cathode type herein provided, comprises a conventional enclosing vessel or envelope having suitable ionizable gas therein. A cathode 12, in the preferred embodiment, is in the form of a cylinder, and an anode 13, also in the preferred embodiment, is in the form of a rod-shaped wire directed along the axis of the cylindrical cathode 12. This form of construction enables a large cathode area to be enclosed in a small envelope.

Suitable means are provided for supporting the cathode 12, such as welding the cathode 12 to a pair of supporting wires 14 and 15, which extend through the press-end 16 of the envelope 11. It is intended that the supporting wires 14 and 15 be quite rigid so that they may be used to position the cathode 12 in the envelope 11 during assembly. After the press 16 has been formed, one of the supporting wires may be clipped off near the press-end, while the other supporting wire provides a cathode lead-in-connection. The supporting wires 14 and 15 extend slightly beyond the end of the cathode 12 at the seal-off end 17 of the envelope 11.

For accurately positioning the cathode 12 and the anode 13 relative to one another, a suitable disc such as mica disc 18 is provided having three aligned punched holes in it for inserting therein, the wire anode 13 and the supporting wires 14 and 15. The supporting wires 14 and 15 after being inserted in the mica disc 18 are

2

crimped or bent to secure the disc thereto. The anode 13 extends through the center hole in the mica disc 18, thereby accurately positioning the anode 13 and the cathode 12.

According to the invention, an auxiliary control electrode such as starter-anode 19, which is formed of a rod-shaped wire, extends through the press 16 and terminates before reaching a bent or transverse portion 20 of the cathode supporting wire 15. The distance between the starter-anode 19 and the anode 13 is greater than the distance between the cathode 12 and the anode 13. Also, the starter-anode 19 to cathode 12 gap is located outside of the main anode 13 to cathode 12 discharge space. This construction enables the starter-anode 19 to be free after ionization has transferred to the main gap, and the starting potential has been removed from the starter-anode 19. Consequently, the starter-anode 19 being positioned outside of the main discharge space does not acquire a potential dependent upon the space charge in the main discharge space. Heretofore, the potential acquired by the starter-anode of previously known tubes, by reason of their position in the main discharge space, has seriously hampered the design of circuits wherein a number of such tubes are interconnected so as to be interdependent, such as in a counting chain. In such circuits the potential on the starter-anode of an ionized tube may greatly reduce the operating limits of another tube connected thereto by biasing it unfavorably.

In operation, suitable potential is initially impressed on the starter-anode 19 to initiate ionization between the cathode supporting wire 15 and the starter-anode 19. With low values of starter-anode current the discharge is confined to the portion of cathode supporting wire 20 that is immediately adjacent to the starter-anode. With increasing values of starter-anode current the discharge spreads along the cathode wire 20 and eventually extends to the cathode cylinder 12. The value of starter-anode current necessary to effect transition of the discharge to the main anode is dependent on the potential between the main anode and cathode, just as it is in conventional tubes of this type. Once the discharge has transferred to the main gap the potential impressed on the starter-anode may be removed. The discharge is now confined within the cathode cylinder, leaving the starter-anode virtually free.

It is to be understood that modifications and variations may be effected without departing from the scope of the appended claims.

What is claimed is:

1. A cold cathode type gaseous discharge tube comprising an envelope enclosing a cathode, an anode, and a starter-electrode, a pair of rods supporting said cathode and extending through the envelope of said tube, said anode being in the form of a rod and mounted along the longitudinal axis of said cathode and extending through the envelope of said tube, said cathode including a cylindrical shaped portion encompassing a space within itself including the electron gathering portion of said anode said pair of rods flaring outwardly away from the anode at the point of the cathode support, said starter-electrode remotely situated outside of said cathode encompassed space and longitudinally disposed in close proximity to the axially remote portion of one of said supporting rods and forming a starter gap therewith, to effectively confine the discharge path of the emitted electrons during conduction between said plate and said cathode within said cathode cylinder encompassed space for keeping said starter-electrode free of said emitted electrons.

2. A cold cathode type gaseous discharge tube comprising an envelope enclosing a cathode, an anode, and

a starter-anode, said cathode being in the form of a cylinder, a pair of rods supporting said cathode and extending through said tube, said anode being in the form of a rod and longitudinally mounted within and along the axis of said cathode, the portion of said anode which is mounted within said cathode cylinder forming a main discharge gap with inner surface of said cathode cylinder, said starter-anode being in the form of a rod and extending through said tube and mounted independent of said cathode and said anode, said supporting rods flaring outwardly from the point of support at one end of said cathode cylinder before passing through said tube, said control electrode terminating within said tube at a remote distance from said main discharge gap near said flared out portion of one of said supporting rods, 15 closing means, the free ends of said supporting rods co-operating with said closing means to effectively close the

other end of said cylindrical cathode, the flared portions of said supporting rods effective to confine the electrical field existing during discharge of said tube within said cylindrical cathode for confining the emitted electrons within said main discharge space and thereby preventing said emitted electrons from impinging upon the starter-electrode and creating a potential thereon.
